UNITED STATES PATENT OFFICE

2,523,388

TOP STOP ATTACHING MACHINE

Alfred G. Natzke, John Willetts, and John Frykberg, New York, N. Y., assignors to Lamar Slide Fastener Corp., New York, N. Y., a corporation of New York

Application June 18, 1945, Serial No. 600,068

12 Claims. (Cl. 153—1)

1

This invention generally relates to the manufacture of slide fasteners and more specifically to mechanisms for attaching top stops to the tape of fastener stringers, at the end of the rows of fastening elements.

The general object of the invention is to provide a novel and improved machine of the character aforesaid, whereby strong top stops may be securely clamped to the tapes of slide fastener stringers without damage thereto, the machine being particularly adapted for use with preformed top stops of the type comprising spaced parallel gripping jaws.

Another object of the invention is to provide a machine of the character described which is of comparatively simple construction, dependable in use, capable of continued rapid operation, so arranged as to permit ready substitution of parts whenever required because of wear or other causes, and suitable either for manual or power operation.

A further object is to provide a top stop attaching machine embodying novel means for controlling and insuring the supply of preformed top stops and the feeding thereof to a fixed position for successive displacement therefrom to a position for clamping to the tape of fastener stringers, and novel means for effecting the transfer of the top stops to the clamping position.

It is also an object of the invention to provide a machine embodying a vertically reciprocable member from which both the supply and feeding controlling mechanism and the means for displacing the top stops to clamping position are simultaneously actuated, thereby insuring synchronized operation of the various cooperating mechanisms while avoiding undue complexity of structure.

These and other related objects will become apparent in the following description of the invention illustrated in the drawings, wherein:

Fig. 1 is a side perspective view of a top stop attaching mechanism according to the invention.

Fig. 2 is a further perspective view of the same mechanism seen from the opposite side.

Fig. 3 is a fragmentary vertical sectional view on line 3—3 of Fig. 5.

Fig. 4 is a fragmentary vertical sectional view similar to Fig. 3 illustrating the position of a top stop and elements of the mechanism acting thereon at the time of clamping of the top stop.

Fig. 5 is a front elevation of the mechanism.

Fig. 6 is a similar front elevation showing the position of elements of the mechanism at the time of clamping of the top stop.

2

Fig. 7 is an enlarged cross-sectional view on line 7—7 of Fig. 5 illustrating the structure of the chute.

Fig. 8 is an enlarged fragmentary plan view, partly in section, on line 8—8 of Fig. 5.

Fig. 9 is an enlarged sectional view on line 9—9 of Fig. 5.

Fig. 10 is an enlarged sectional view on line 10—10 of Fig. 5 illustrating details of the mechanism.

Referring now in detail to the drawings and in the first place to Figs. 1 and 2, it will be seen that a machine according to the invention comprises a press adapted to be mounted on a bench, or 15 the like, which embodies a supporting foot 10 and a standard 11 extending upwardly from the foot and terminating in a head 12 which carries a vertically reciprocable member 13. The reciprocation of the member 13 is effected by means of any suitable mechanism outside of the scope of the present invention and not shown in the drawings, which may be actuated through a foot pedal or the like, or, if preferred, suitably connected for power operation.

25 A member or block 14 is suitably fastened at its central portion 15 to the lower end of the member 13 for reciprocation therewith, and is formed with an outwardly projecting portion 16 which is provided with a vertical bore 17 receiving the stem of a downwardly projecting clamping die 18 removably secured within said bore. In the embodiment illustrated, the die 18 is suitably shaped for clamping to the tape of fastener stringers top stops of the type comprising 30 parallel spaced jaws interconnected by a short yoke portion, said top stops being conveyed to a predetermined position for action by the clamping die by means of the mechanism hereafter described.

35 The portion 20 of the block 14 opposite to the die-carrying portion 16, carries a member 21, which projects downwardly in parallel spaced relation to the clamping die 18 and embodies at its lower end an inclined surface 22 acting as a cam for the purpose that will become later apparent (see particularly Figs. 2 and 3). For the sake of clarity, the member 21 will be hereafter referred to as a cam member.

40 A base member 24 is removably and adjustably mounted on the foot 10 of the machine, as by means of bolts 25, below the reciprocable block 14, and is provided with a recess 26 (see Figs. 3 and 4) adapted to receive the free end of the cam member 21 aforementioned.

45 The base 24 is partly machined to provide a

smooth upper surface to which there is fastened, as by means of screws 28, a plate 30. Said plate is formed, in correspondence with the recess 26 of the base 24, with a rectangular aperture 31 which is somewhat wider than the recess so as to provide shoulders 32 underneath the aperture 31 inwardly of the longitudinal walls of this latter. The plate 30 is provided with a horizontal groove or guideway 34 having a width only slightly greater than that of a top stop and extending outwardly from the aperture 31 in vertical alignment with the clamping die 18, the portion of the plate 30 extending below and beyond the clamping die being of reduced height as shown at 35 to define a shallow groove portion 36 the depth whereof substantially corresponds to the thickness of one of the gripping jaws of a top stop (see Figs. 2 to 4).

A plate 38 is screwed to the plate 30 inwardly of the die 18, and is formed with an integral extension 39 projecting into the groove 34 to define with the bottom and side walls of this latter a passage so dimensioned as to insure that the top stops propelled therethrough in the manner hereafter described will maintain the position shown in Fig. 3. The inner edge of the plate 38 is laterally spaced relative to the underlying edge of the plate 30 defined by the aperture 31 thereof, to leave exposed the end portion 40 of the groove 34 and provide an entrance for the top stops supplied thereto in succession, in the manner later described, for subsequent displacement to the clamping position directly underneath the die 18. The plate 38 also carries a projecting pin 42 adapted to engage the upper jaw of the top stops at the clamping position, to prevent objectionable displacement thereof in the shallow portion 36 of the groove 34.

The displacement of the top stops from the position of Fig. 3 to the clamping position is effected by means of a horizontally reciprocable member 44 which may be designated as the top stop propelling member. Said member comprises a vertical element which projects into the recess 26 of the base 24 and is formed with an enlarged head 45 extending between the longitudinal walls of the aperture 31 in the plate 30 and slidably supported by the shoulders 32 defined as aforementioned. The head embodies a cam surface 46 engageable by the cam surface 22 of the cam member 21 and has a horizontal extension 48 in alignment with the groove 34. Said extension is normally withdrawn from the groove to terminate adjacent the inner end thereof, and is adapted to engage and displace the top stops from the position of Fig. 3 to that of Fig. 4 in the forward movement of the member 44 caused by the action of the cam surface 22 on the cam surface 46 during the descent of the cam member 21. The member 44 is maintained in contact with the cam member 21 and is returned to its initial position by a spring 50 associated with a stud 52 and received within a bore 51 in the base 24.

As will be apparent from the foregoing description, during the downward stroke of the block 14 carrying both the clamping die 18 and the cam member 21, this latter will actuate the top stop propelling member 44 and cause the same to move the top stop to the clamping position directly underneath the die in which it will straddle the tape of a fastener stringer placed upon the portion 35 of the plate 30 as shown in Fig. 1, whereupon the top stop will be engaged by the die and its jaws clamped to the opposite faces of the tape. The die 18 is formed with a groove 54 which re-

ceives the pin 42 in the lowermost position of the die, and the plate 30 may be provided with an abutment 55 as shown in Figs. 1 and 3, adapted to engage the end scoop of a stringer to insure proper spacing of the top stop relative to said scoop. The fastener stringers may be fed manually or suitable automatic feeding means may be provided if desired.

The mechanism for insuring constant supply of top stops through the entrance portion 40 of the groove 34 to the position of Fig. 3, for engagement by the propelling member 44, will now be described. Reference is made particularly to Figs. 5 to 10.

A vertical stationary disc 60 is secured to the base 24, as by means of screws 61, at a right angle to the longitudinal axis of the recess 26. The disc 60 is cut to define a portion 62 extending in juxtaposition to the plate 38 over the entrance end 40 of the groove 34. The front of the disc is provided with a circular groove 64 adapted to accommodate the top stops in a predetermined position, for sliding movement therealong, the end of said groove 64 in the disc portion 62 being in vertical alignment with the entrance end 40 of the groove 34 so that the top stops after traveling from a point of entrance through a portion of the groove 64 forming a passageway in the disc (upper left quadrant) will be free to drop into the groove 34, to be successively engaged and displaced to the clamping position of Fig. 4 in the manner hereinbefore described, during the operation of the machine.

The top stops are admitted to the groove 64 through a radial opening 65 of the disc which has associated therewith the lower end of a top stop conveying chute.

The chute, generally indicated at 66, comprises a blade 67 which is operatively connected at its upper end and to a suitable hoppering device (not shown) adapted to deposit preformed top stops 68 of the type aforementioned onto the blade with their jaws adjacent the opposite faces of the blade and their yoke portion resting on the upper edge thereof. The blade 67 is suitably inclined to cause the top stops to slide therealong by gravity and has fastened thereto a plurality of members 69 supporting a strip 70 disposed at a right angle to the blade and sufficiently spaced therefrom to permit free downward movement of the top stops along the blade while retaining the same thereon (see Fig. 7). The vertical lower end portion of the blade is secured, as at 71, to a fixed member 72 carried by the disc 60 and partially extends into the radial opening 65 of the disc. The blade is so curved as to direct the top stops 68 into the opening 65 with their jaws in a vertical position and extending toward the front of the disc 60 (see Fig. 8) so that the top stops after travelling in the passageway formed by the groove 64 of the disc through an arc of approximately 90° will enter the end 40 of the groove 34 with their jaws in a horizontal position and their yoke portion adjacent the extension 48 of the propelling member 44, as illustrated in Fig. 3.

The top stops are maintained within the passageway by a cover plate 74 removably secured to the disc 60, as by means of screws 75, and preferably made of a transparent plastic material, as illustrated in Figs. 5 and 9.

Means are provided for controlling the rate of supply of the top stops 68 from the chute 66 to the passageway and for facilitating the feeding of the top stops therethrough to the entrance end 40 of the groove 34.

For this purpose, a shaft 76, freely mounted in the disc 60, carries for rotation therewith a sector 78 fastened to the enlarged end portion 79 of the shaft and juxtaposed to the front of the disc. The shaft 76 projects rearwardly from the disc 60 to carry a lever 80 fastened thereto. The lever has pivotally mounted at its free end, as shown at 81, a vertical rod 82 passing through an opening 83 in a bracket 84 which is fastened at 85 to the portion 20 of the block 14 and is therefore vertically reciprocable simultaneously with the clamping die 18 and the cam member 21. The rod 82 has fixed thereon collars 86, 87 respectively located below and above the bracket 84, a coil spring 88 surrounding the rod 82 between the bracket 84 and the collar 87.

The rear face of the sector 78 is formed with a projecting arcuate rib 90 slidable within a portion of the groove 64 of the disc 60 (see Fig. 10) and terminating in a tongue 91 projecting from the sector, as clearly shown in Figs. 5 and 6. In the inoperative condition of the machine to which there corresponds an uppermost position of the block 14 and bracket 84 shown for instance in Fig. 5, the spring 88 urges the collar 87 and the rod 82 upwardly thereby maintaining the sector 78 in an angular position wherein the tongue 91 extends beyond the radial opening 65 of the disc groove 64 underneath the chute end (see Fig. 5) thereby preventing entrance of top stops into the passageway portion of the groove.

In the descent of the block 14 and associated elements, the bracket 84 will engage the collar 86 of the rod 82 to depress the same and therefore cause rotation of the sector 78 by an amount sufficient to withdraw the tongue 91 from the opening 65 (see Fig. 6), thereby permitting supply of a top stop from the chute to the passageway, while a top stop already in the groove 34 is displaced to the clamping position and then clamped to the fastener stringer through the action of the cam member 21, propelling member 44 and die 18 actuated simultaneously with the bracket 84.

The sector 78 is returned to its initial position of Fig. 5 by the spring 88 and the supply of top stops again interrupted during the upward stroke of the block 14 and associated elements, the tongue 91 of the sector then engaging the last top stop received from the chute and urging the same away from the point of entrance. If, as is normal in the operation of the machine, the passageway portion of the groove 64 is substantially filled with top stops, all said top stops will be urged toward the entrance end 40 of the groove 34 by the action of the tongue 91, and movement of the lowermost top stop to the position of Fig. 3 will be insured as soon as the extension 48 of the member 44 is withdrawn from the groove 34 upon return of the member to its initial position. It is therefore apparent that the supply of top stops is effected at a rate corresponding to the rate of consumption thereof and that gradual feeding of the top stops to the groove 34 is insured through the operations of the sector 78.

The invention has been described and illustrated substantially with reference to a preferred embodiment thereof and to the use of top stops of a specific character. However, it is understood the invention may find application in connection with the clamping of elements other than the top stops illustrated, and that numerous changes and modifications may be made in the structures disclosed without departing from the spirit of the invention or exceeding the scope of the claims.

We claim:

1. In a machine for attaching top stops to slide fastener stringers, a vertically movable clamping die, a fixed element, a substantially horizontal guideway in said fixed element, a movable member actuatable to engage a top stop positioned at one end of said guideway and to propel the same through the guideway to a position underneath said clamping die for clamping by this latter to a slide fastener stringer, means for actuating said horizontally movable member in synchronism with the clamping die, a chute carrying top stops, an inclined passageway connecting said chute and guideway for conveying top stops from said chute to said end of the guideway, and means operatively connected for movement in synchronism with said clamping die and periodically interposed between said chute and passageway for controlling the delivery of top stops to said passageway.
2. In a machine for attaching top stops to slide fastener stringers, a clamping die and a cam member mounted for simultaneous vertical reciprocation, a fixed element, a substantially horizontal guideway in said fixed element, a reciprocable member actuatable by said cam member to engage a top stop positioned at one end of said guideway and to propel the same through the guideway to a position for clamping by the clamping die to a slide fastener stringer, means for feeding top stops to said end of the guideway and means operatively connected for movement in synchronism with said clamping die and periodically interposed between the feeding means and the said end of the guideway for controlling the supply of top stops to said end of the guideway at a rate corresponding to the rate of consumption by the clamping die of the top stops.
3. In a machine for attaching top stops to slide fastener stringers, a clamping die and a cam member mounted for simultaneous vertical reciprocation, a fixed element, a substantially horizontal guideway in said fixed element, a reciprocable member actuatable by said cam member to engage a top stop positioned at one end of said guideway and propel the same through the guideway to a position underneath said clamping die for clamping by this latter to a slide fastener stringer, means for feeding top stops to said end of the guideway, fixed means engaging the top stop at said position underneath the clamping die to prevent displacement of the top stop during clamping, and means operatively connected for movement in synchronism with said clamping die and periodically interposed between the feeding means and the said end of the guideway for controlling the supply of top stops into said end of the guideway.
4. In a machine for attaching top stops to slide fastener stringers, a clamping die and a cam member mounted for simultaneous vertical reciprocation, a fixed element, a substantially horizontal guideway in said fixed element, a reciprocable member actuatable by said cam member to engage a top stop positioned at one end of said guideway and to propel the same through the guideway to a position underneath the clamping die for clamping by this latter to a slide fastener stringer, a source of supply for top stops, an inclined passageway for conveying top stops from the source of supply to said end of the guideway, and means operatively connected for movement in synchronism with said clamping die and periodically interposed between said source of supply and said passageway for controlling the rate

of delivery of the top stops from the source of supply to said passageway.

5. In a machine for attaching top stops to slide fastener stringers, a clamping die and a cam member mounted for simultaneous vertical reciprocation, a fixed element, a guideway in said fixed element, a horizontally reciprocable member, actuatable by said cam member to engage a top stop positioned at one end of said guideway and to propel the same through the guideway to a position for clamping by the clamping die to a slide fastener stringer, an inclined passageway registering with said end of the guideway, a chute carrying top stops for conveying top stops to said passageway, and means operatively connected with said horizontally reciprocable member and actuated in synchronism with the horizontally reciprocable member for permitting delivery of top stops from said chute to said passageway at each reciprocation of said member.

6. In a machine for attaching top stops to slide fastener stringers, a vertically reciprocable member carrying a clamping die, a fixed plate, a substantially horizontal guideway in said fixed plate, a movable member embodying a portion in alignment with and extending to a point adjacent one end of the guideway in the normal position of the member, a cam member carried by said vertically reciprocable member effective in the downward stroke of this latter to actuate said horizontally movable member to cause said portion thereof to engage a top stop positioned at said end of the guideway and propel the same through the guideway to a position underneath the clamping die for clamping by this latter to a fastener stringer, resilient means for returning the horizontally movable member to its normal position during the upward stroke of the vertically reciprocable member, means for feeding top stops to said end of the guideway and means operatively connected with said vertically reciprocable member and said top stop feeding means and interposed between said feeding means and said end of the guideway for periodically supplying top stops to said end of the guideway.

7. In a machine for attaching top stops to slide fastener stringers, a vertically reciprocable member carrying a clamping die, a fixed plate, a guideway in said fixed plate, a horizontally movable member embodying a portion in alignment with and extending to a point adjacent one end of the guideway in the normal position of the member, a cam member carried by said vertically reciprocable member effective in the downward stroke of this latter to actuate said horizontally movable member to cause said portion thereof to engage a top stop positioned at said end of the guideway and propel the same through the guideway to a position underneath the clamping die for clamping by this latter to a fastener stringer, resilient means for returning the horizontally movable member to its normal position during the upward stroke of the vertically reciprocable member, a chute for top stops, an inclined passageway between said chute and said end of the guideway, and means operatively connected with said vertically reciprocable member and interposed between said chute and passageway for periodically delivering top stops from the chute to said passageway in synchronism with said vertically reciprocable member at a rate corresponding to the rate of consumption of the top stops by the clamping die.

8. In a machine for attaching top stops to slide fastener stringers, a vertically reciprocable mem-

ber carrying a clamping die, a fixed plate, a guideway in said fixed plate, a horizontally movable member embodying a portion in alignment with and extending to a point adjacent one end of the guideway in the normal position of the member, a cam member carried by said vertically reciprocable member effective in the downward stroke of this latter to actuate said horizontally movable member to cause said portion thereof to engage a top stop positioned at said end of the guideway and propel the same through the guideway to a position underneath the clamping die for clamping by this latter to a fastener stringer, resilient means for returning the horizontally movable member to its normal position during the upward stroke of the vertically reciprocable member, and means for supplying top stops to said end of the guideway, said means comprising an inclined passageway registering with the end of the guideway, a chute for top stops leading to said passageway and a mechanism interposed between said chute and said passageway, operatively connected with and periodically actuated in synchronism with the vertically reciprocable member aforesaid for controlling the rate of delivery of the top stops from said chute to said passageway.

9. A machine for attaching top stops to slide fastener stringers comprising a vertically reciprocable clamping die, a fixed element, a guideway in said fixed element, a horizontally reciprocable member for engaging a top stop positioned at one end of said guideway and propelling the same through the guideway to a position underneath the clamping die for clamping by this latter to a fastener stringer, means for actuating said horizontally reciprocable member in synchronism with the clamping die, a chute for top stops, an inclined passageway between the chute and guideway for conveying the top stops from said chute to said end of the guideway, an oscillatingly movable member normally isolating said chute from said passageway, and means operatively connected with said horizontally reciprocable member for periodically displacing said movable member from the normal position thereof in synchronism with the actuation of the horizontally reciprocable member to permit periodical delivery of top stops to the passageway.

10. A machine for attaching top stops to slide fastener stringers comprising a vertically reciprocable clamping die, a fixed element, a guideway in said fixed element, a horizontally reciprocable member for engaging a top stop positioned at one end of said guideway and propelling the same through the guideway to a position underneath the clamping die for clamping by this latter to a fastener stringer, means for actuating said horizontally reciprocable member in synchronism with the clamping die, an inclined passageway registering with said end of the guideway, a chute for delivering top stops to the upper end of said passageway, a movable member having a portion normally extending into the upper end of the passageway to isolate the chute therefrom, and means operatively connected with said horizontally reciprocable member for oscillatingly displacing said movable member to withdraw said portion thereof from the upper end of the passageway at each reciprocation of the horizontally reciprocable member aforesaid.

11. A machine for attaching top stops to slide fastener stringers comprising a vertically reciprocable member, a clamping die carried by said vertically reciprocable member, a fixed plate, a guideway in said plate, a horizontally recipro-

cable member actuatable to engage a top stop positioned at one end of said guideway and propelling the same through the guideway to a position underneath the clamping die for clamping by this latter to a slide fastener stringer, means for actuating said horizontally reciprocable member in synchronism with the clamping die, a chute, an arcuate passageway for conveying top stops from said chute to said end of the guideway, a pivoted member having a portion normally extending into said passageway to isolate the chute therefrom, and means actuated from the vertically reciprocable member aforesaid for rotating said pivoted member to withdraw said portion thereof from the passageway and permit delivery of top stops thereto.

12. In a machine for attaching top stops to slide fastener stringers, comprising a vertically reciprocable clamping die and means actuated in synchronism with said clamping die for engaging a top stop at a fixed position and propelling the same to a position for clamping by the clamping die to a slide fastener stringer, a stationary element, a chute for top stops, an arcuate passageway in said stationary element associated with said chute for conveying top stops therefrom to said fixed position, a member pivoted on the sta-

tionary element and having a portion normally extending into said passageway to isolate the chute therefrom, and means actuated in synchronism with the clamping die for periodically rotating said pivoted member to withdraw said portion thereof from the passageway and permit delivery of top stops thereto.

ALFRED G. NATZKE.
